UNITED STATES PATENT OFFICE.

JOHN TOPALIAN, OF NEW YORK, N. Y.

VEGETABLE-CUTTING APPARATUS.

1,263,152.

Specification of Letters Patent. Patented Apr. 16, 1918.

Original application filed March 16, 1917, Serial No. 155,167. Divided and this application filed October 5, 1917. Serial No. 194,950.

To all whom it may concern:

Be it known that I, JOHN TOPALIAN, a subject of the Sultan of Turkey, and a resident of the borough of Manhattan, city, 5 county, and State of New York, have invented certain new and useful Improvements in Vegetable-Cutting Apparatus, of which the following is a specification.

My invention relates to means for cutting 10 and shaping vegetables as set forth in my concurrent application Serial No. 155,167, filed March 16, 1917, of which the present application is a subdivision appertaining more particularly to the dies, etc., used for 15 the formation of "Bardelaise" potatoes and similar products, the invention consisting in the specific construction and arrangement of parts described and claimed, and a distinctive feature being the series of stationary open work oval matrices used in 20 conjunction with the concave strippers, etc., as hereinafter fully set forth.

In the accompanying drawings,

Figure 1, is an isometrical perspective of 25 a hand press adapted to the practical requirements of my invention;

Fig. 2, is a horizontal section thereof taken on a plane immediately below the cross head which unites the upper ends of 30 the corner standards, and looking downward;

Fig. 3, is a horizontal section taken on a plane immediately below the pusher head, and also looking downward;

Fig. 4, is a plan of the female "Bardelaise" die, or die for cutting of convex-sided pieces;

Fig. 5, is a section taken upon plane of line 5—5, Fig. 4;

Fig. 6, is a top view of the male die or "Bardelaise" stripper;

Fig. 7, is a view of the under side thereof;

Fig. 8, is an end view thereof;

Fig. 9, is a side elevation of a portion 45 thereof;

Fig. 10, is a sectional view showing the Bardelaise die seated in the press, and the stripper extending through the matrices of the female die;

Fig. 11, shows the shape of the product of the Bardelaise matrices;

Fig. 12, is an edge view of the elliptical core cutter;

Fig. 13, is a side elevation thereof, partly 55 broken away.

The press P, is mounted upon a suitable table or base B, supported upon a leg or pedestal B', or in any other suitable manner. Rigidly attached to the base B, are four standards b, b, united integrally at top 60 by a cross head b'. Rigidly attached to and between the standards b, b, and intermediate between the base B, and the cross head b', is the seat for the support of the female dies used in shaping the potato or 65 other vegetable products. For convenience I shall hereinafter confine my description to the formation and manipulation of potato products with the understanding that I am not limited thereto, since other vegetables may be so treated as before stated. 70

The female die seat consists essentially of the horizontal flanges a, and vertical walls or flanges a', the horizontal flanges a, being formed with notches or recesses a² for the 75 purpose hereinafter set forth.

C, is the platen on the under side of which the male dies, forwarders, and strippers are mounted as required for use. This platen member C, is rigidly attached to the 80 lower end of a push rod c, slidably mounted in the central bearing b², on the cross head b', as shown more particularly in Fig. 1, the upper extremity of the said rod c, being provided with a knob or handle c', by 85 which it may be depressed manually if desired against the resistance of retractile springs c², c², (see Figs. 1 and 2) attached to the cross head b', and to the platen member C. The platen member C, may also be 90 depressed against the resistance of said retractile springs c², c², by means of a hand lever L, or equivalent mechanical expedient. The hand lever L, shown is fulcrumed on a link lever L', in turn fulcrumed on a rear 95 cross rod b³, (Fig. 3) so that the compound lever L, L', thus formed, can adapt itself readily to the vertical movement of the platen C, and rod c, which latter the hand lever L, straddles as shown in Fig. 2. Thus 100 the depression of the hand lever L, forces the platen C, downward against the resistance of the springs c², which tend constantly to maintain said platen C, in its highest position above the die seat a, a'. 105

Below the female die seat a, a', the space between the standards b, is inclosed at the rear and sides, and is formed with an inclined chute a³, which directs the material from the dies to a receptacle D, supported 110

for the purpose on arms b^4 , (one of which is shown in Fig. 1) on either side of the table B. D', is a supply pan in which the potatoes may be stored temporarily in convenient position for introduction by hand into the press P,—said supply pan D', being supported on bracket rods d, (one of which is shown in Fig. 1) or in any other desired or convenient manner.

10 c^3 , c^3 , are holes or sockets formed in the platen C, for the reception of the suspender studs s, s, on the back plates of the several male dies, etc., said suspender studs s, s, being formed with transverse holes s', s', for 15 the reception of coupling pins c^4 , c^4 , by means of which said back plates may be secured to the under side of the platen C.

a^4 , is a binding screw for holding the female dies rigidly on the seat a , a' , when desired. The platen C, is formed with arms c^5 , c^5 , the ends of which straddle the guide rods b^5 , b^5 , so as to prevent said platen from turning on its axis.

20 In the preparation of "Bardelaise" potato, formed from split oval potato cores made by the use of the oval core cutter F, with a blade f^8 , shown in Figs. 12 and 13, a female die F', shown in Figs. 4, 5 and 10, is used, in conjunction with a male die or 25 follower F², shown in Figs. 6 to 9 inclusive. The female die F', is provided with a series 30 of oval matrices f, f, formed by bent blades each flexed and arranged in pairs, back to back, leaving clearance spaces between the 35 said matrices to prevent the obstruction of the dies by trimmings as shown in Fig. 4, and the oval core of potato is pressed through these matrices f, f, by concave strippers f', f', upon the lower ends of studs

f^2 , f^2 , attached to the back plate f^3 , of the 40 male die F²,—said back plate being formed with the usual suspender studs s, s, for attachment to the press platen C, as before described. The faces of the strippers f', f', are made concave to conform to the shape 45 of the oval core made by the cutter F; and the shape of the resultant product is shown in Fig. 11.

The female die F', for "Bardelaise" potato is of course supported in the press upon 50 the seat a , a' , as shown in Fig. 10, and it is formed with vertical flanges f⁴, f⁴, which limit the downward stroke of the male die F².

55 It is to be noted that the female die seat a , a' , is wide open centrally, so that while it affords ample support for the dies, the shaped potato products and the resultant trimmings are free to descend to the chute a^3 . Also that the pressure on the reciprocating platen C, and consequently on the male dies, etc., is entirely within the control 60 of the operator, and that the retractile movement of said platen is automatic.

65 What I claim as my invention and desire to secure by Letters Patent is,

In a device of the character described, a female die seat, a female die having a series of flexed blades arranged in pairs back to back, forming elliptical matrices, and having clearance spaces between the matrices to prevent obstruction of the dies by trimmings.

JOHN TOPALIAN.
